(57) CLAIM

The ornamental design for a lighting fixture, as shown and described.

DESCRIPTION

FIG. 1 is a front perspective view of a lighting fixture;
FIG. 2 is a top view thereof; and,
FIG. 3 is a bottom view thereof.

The broken lines in all views are included for the purpose of illustrating portions of the lighting fixture that form no part of the claimed design.

1 Claim, 1 Drawing Sheet

FIG. 3
